E. F. McCUE

COVER FOR CONDUITS

Filed Oct. 19, 1926

INVENTOR:
Edward F. McCue
BY
Chas. M. C. Chapman,
ATTORNEY.

UNITED STATES PATENT OFFICE.

EDWARD F. McCUE, OF MAMARONECK, NEW YORK.

COVER FOR CONDUITS.

Application filed October 19, 1926. Serial No. 142,770.

This invention has reference to means for locking and retaining in place a closure, cover or cap for tubular openings of any character, and particularly relates to means 5 for removably holding caps or closures on a fresh air inlet.

My invention is adapted for application to strainers of various kinds, water mains and pipes, air and other conduits.

10 Among the objects of my invention may be noted the following: to provide a cover, closure or seal for conduits or inlet pipes which is simple in form, economical to produce, strong and durable, and includes a 15 simple, strong, durable and economical means for holding the cover, cap or closure removably to the conduit; to provide a device or means, of the character noted in the foregoing, which may act either as a seal, 20 a drain, a strainer or an inlet, and which eliminates all obstructions, projections or protuberances on the outside of the conduit or the surface of the closure; to provide, in a device such as set forth in the foregoing, a 25 means which can be readily manipulated from the outside of the closure and the free end of the conduit for holding the closure rigidly and firmly in position, and yet is adapted to be quickly released for removal 30 by a simple implement; and to provide means, such as outlined in the foregoing, enabling the use and utilization of "scrap" pieces of pipe, or sections of pipe which would ordinarily be thrown away or discarded 35 as useless, and which can be quickly and easily applied for closure or capping purposes.

With the foregoing objects in view, and others which will be detailed during the 40 course of this description, my invention consists in the parts, features, elements and combinations thereof hereinafter described and claimed.

In order that my invention may be clearly understood, I have provided drawings 45 wherein:

Figure 1 is a view showing a conduit in section with my closure and holding means applied to the free end thereof, the parts 50 also being in section;

Figure 2 is a view similar to Figure 1, showing the holding means set to prevent the removal of the closure; and

Figure 3 is a view showing the parts of 55 Figures 1 and 2 in transverse sectional elevation on the line 3-3 of Figure 2.

Referring to the drawings, the numeral 1 indicates a conduit of any desirable character. It may be a drain-pipe, sewer-pipe, air-inlet or manhole framing, and it may be full 60 section or merely "scrap" section. The outer end of the pipe is ordinarily enlarged or flanged for strength; but, I have shown my invention applied to a waste or "scrap" section, which would ordinarily be discarded 65 or thrown away, and is, therefore, devoid of such flange or enlargement. The closure, of my invention, has its circumferential margin 3 set flush on the end of the conduit so as to present a smooth, obstructionless surface. 70 Preferably, for strength, the closure is arched within the marginal portion 3, and its solid center 4 is provided with an aperture outwardly flared for the reception of a similarly formed head 5 of a long screw 6 75 which passes through the aperture and is the manipulating means for the locking members. The closure may be perforated, as at 7, or may be solid, according to the use 80 to which my invention is adapted.

An angular bracket is provided which has a flat, central portion 8 extended into resilient legs 9 arranged at an obtuse angle to the central portion. The terminals of the resilient legs are bent at an obtuse angle to 85 the latter and are made extensive, as at 10, for the engagement of an operating and locking bar 11. The terminals 10 are made sufficiently extensive to enable the bar 11 to be shifted by the screw 6 so as to release the 90 terminals without losing engagement with the bar when the latter is shifted to release the closure, the resilience of the legs 9 causing the terminals 10 to normally clamp the bar and maintain engagement therewith. 95 The screw 6 extends through an aperture 12 in the flat, central portion of the angular bracket, and also extends through a threaded aperture in the locking bar 11.

By turning the screw, the locking bar 11 100 is caused to travel along the terminals 10 and into engagement with the inner surfaces of the resilient legs 9, causing them to flex and be distended by the wedging action between the bar and the legs. This action 105 drives the flat terminals 10 into engagement with the inner surface of the conduit 1 and also forces the central, flat portion 8 into engagement with the inner surface of the closure, and also causes the head of the 110 screw 5 to sink within the flared aperture in the solid part of the closure. Thus, as shown

in Figure 2, the closure, screw, bracket and bar, by the simple manipulation of the screw, are forced firmly and rigidly into co-operative engagement, and the flat terminals 5 10 of the bracket are driven firmly against the inner surface of the conduit. It requires only a few turns of the screw to either lock or release the closure. When the closure is released, insertion of an implement, either 10 in one of the apertures or under the head of the screw, coupled with an outward pull, will enable the cover to be removed together with the entire locking device.

While I have shown the closure apertured, it may be made solid; and the marginal portion 3 of the closure may be grooved to cooperate with a corresponding portion at the end of the conduit, this forming a seal. Also, the bracket may be provided with several more legs and the locking bar constructed to engage and flex them all simultaneously; but, no change need be made in either the closure or screw, the latter having the smooth portion 13 adjacent the head to 25 permit the bracket to freely slide toward and from the closure.

Having thus described my invention, what I claim and desire to secure by Letters Patent is:

30 1. Means for closing or covering conduits comprising a cap having a central, smooth-

bore aperture flared outwardly, in combination with an angular bracket having a pair of resilient legs adapted to engage the inner surface of a conduit, a rigid bar having a central threaded aperture adapted to slide between the legs of the bracket, and a screw having a head snugly fitting the aperture of the cap so as to be flush with the surface of the cap, and having a smooth shank portion sliding freely through the cap and bracket, and also having its threaded portion cooperating with the aperture of the bar whereby, when the screw is turned, all the parts may be forced into intimate relation for the functional purpose described. 45

2. Means for closing conduits comprising a cap having a central aperture, in combination with a bracket having a flat central portion and resilient legs at an obtuse angle thereto, said legs having each a terminal portion extending inwardly at an obtuse angle thereto, a locking bar adapted to operate between the legs and to be normally held by the terminals thereof when in released position, and a screw passing freely through the cap and bracket and engaging the bar to shift the latter along the legs of the bracket to lock all the parts together and to the conduit. 55

EDWARD F. McCUE.
